Fig. 4.

FIG. 5.

FIG. 6.

FIG. 7.

I claim:

The ornamental design for a case for beverage containers, as shown.
